UNITED STATES PATENT OFFICE.

RUDOLPH KLEIN, OF FULTS, AND GEORGE B. RITZEL, OF VALMEYER, ILLINOIS.

MACHINE WRENCH.

Application filed September 13, 1921. Serial No. 500,308.

To all whom it may concern:

Be it known that we, RUDOLPH KLEIN and GEORGE B. RITZEL, citizens of the United States, residing at Fults, in the county of

5 Monroe and State of Illinois, and Valmeyer, in the county of Monroe and State of Illinois, have invented certain new and useful Improvements in Machine Wrenches, of which the following is a specification.

10 The invention appertains to certain improvements in machine wrenches generally, and more particularly to a type of the same adapted for the tightening or loosening up of the nuts of the bolts of railroad rail joints.

15 The principal object of the invention is to provide for a wrench as characterized, and one of a construction and arrangement designed to greatly facilitate the work of the 20 tightening and loosening up of the usual fastening bolts of railroad rails, and which is extremely durable, efficient, easy and rapid in operation.

25 With the foregoing and other objects in view, the invention resides in the certain new and useful construction, arrangement and operation of parts, as will be hereinafter more fully described, set forth in the appended claims, and illustrated in the accompanying drawing, in which:—

30 Figure 1 is a side elevation of a preferred embodiment of the machine wrench,

Figure 2 is a front elevation thereof,

Figure 3 is a top plan view thereof, and,

35 Figure 4 is an enlarged sectional detail of the wrench socket per se.

Referring to the drawings, wherein similar characters of reference designate corresponding parts throughout the several views thereof, the numerals 10 and 11 indicate a pair of vertically spaced frame bars or standards each formed to provide laterally offset lower foot portions 10' and 11', respectively, and the same are connected together, slightly 45 downward from their upper ends, by means of a transverse bar 12, and, immediately above the offset foot portions 10' and 11', by means of a lower transverse bar 13. The vertical bars or standards 10 and 11 are preferably formed of suitable lengths of I-beams, or other similar angle iron or steel, and with the foot portions 10' and 11', and the cross bars 12 and 13, constitute the main frame 50 of the machine wrench. Extending laterally 55 from the lower ends and foot portions of the vertical bars or standards 10 and 11, is an

auxiliary frame formed of upper and lower pairs of horizontal members or bars 14 and 15, respectively, an outer vertical pair of members or bars 16 connecting the outer ends 60 of the pairs of upper and lower members or bars 14 and 15, and an outer pair of upper and lower horizontal members or cross bars 17, the corners of the upper parts of this frame, as formed by the connecting portions 65 of the upper pair of members or bars 14 and the upper of the cross bars 17, being supported from the lower ends of a pair of brace members or bars 18 extending diagonally upward and connecting the standards 10 70 and 11 on the main frame at points below the upper ends thereof.

The two frames thus constructed and arranged constitute the entire frame work of the machine wrench, and the same is to 75 be positioned over a rail joint in a manner so that the lower ends of the standards 10 and 11 rest directly upon the ball of the rail or rails, with the offset foot portions 10' and 11' thereof depending to one side of 80 the latter and resting on the upper face of one flange of the rail or rails, or on the ties supporting the same, the lower auxiliary frame extending outwardly from the rail or rails on the side of the frame from which the 85 nuts are to be threaded onto the bolt fastenings at the joint of adjacent rail sections, or unscrewed therefrom. For securing or otherwise clamping the framework in operative position, a pair of oppositely disposed 90 clamp levers 19 and 20 are provided, and each are formed with lower angularly offset foot portions 21 and 22, respectively, and are pivoted as at 23 and 24 to the standards 10 and 11, the foot portions 21 and 22 engaging the side of the rail or rails opposite to that of the foot portions 10' and 11', of the standards 10 and 11 of the framework, when operated. The levers 19 and 20 have their upper free ends pivotally connected as 95 100 at 25 and 26 to the upper free ends of a pair of manually operated levers 27 and 28, which are curved for a distance downwardly from the pivot connections 25 and 26 and terminate in straight lower portions having 105 hand grips 29 and 30 at their free ends, respectively, the levers 27 and 28 being pivoted as at 31 and 32 to the standards 10 and 11, and to facilitate the manipulation of these levers, the hand grips 29 and 30 are transversely 110 grooved or serrated as shown. In positioning the framework of the machine on the

rail joint, the hand levers 27 and 28 are raised in a manner to draw the upper ends of the clamping levers 19 and 20 inwardly toward the standards 10 and 11, when the 5 foot portions 21 and 22 will be moved outwardly in the opposite direction and away from the foot portions 10' and 11' of the latter, whereby to allow for the free passage of the rail or rails upward between the lat- 10 ter portions of the framework of the machine and the lever foot portions 21 and 22, and into abutting relation with respect to the lower ends of the standards 10 and 11, when, upon lowering the hand levers 27 and 15 28, the foot portions 21 and 22 thereof will be forced against the opposed side of the rail or rails to securely clamp the framework thereto.

The wrench mechanism of the machine 20 and the manner of mounting the same on the framework is, as follows: A cylindrical wrench member or head 33, having a nut engaging socket 34 in one end thereof, is provided with a squared bore 35 in its opposite 25 end for sliding engagement on the free squared end portion 36 of a stub-shaft 37, which is suitably journaled through the lower of the end cross bars 17 of the auxiliary frame, and has keyed on its outer free 30 end a spur gear 38 arranged in mesh with a second and upper spur gear 39, which is, in turn, journaled in the upper cross bar 17 of the auxiliary frame, and the lower cross bar 13 of the main frame, and extends 35 in a plane above and parallel to the stub shaft 37 and the wrench head or member 33. The forward end of the shaft 40, opposite to that on which the gear 39 is keyed, is provided with a small worm gear 41 ar- 40 ranged in mesh with a worm wheel 42 keyed on the lower end of a shaft 43 extending vertically of the main frame, the upper end of the shaft 43 being suitably journaled in the upper cross bar 12 and has on its upper pro- 45 jecting end a beveled gear 44 arranged in mesh with a second beveled gear 45 keyed on a shaft 46 journaled transversely of the upper free ends of the standards 10 and 11, the outer free ends of the shaft 46 being pro- 50 vided with hand cranks 47 and constitute the operating medium of the mechanism, and upon the turning of which, a rotary movement is imparted to the wrench head or member 33 in either direction of the 55 screwing on or off of the nut of a rail fastening bolt to be engaged in the socket 34 of the latter.

With the framework of the machine clamped in proper position, the wrench head 60 or member 33 is to be retracted against the tension of a coiled spring 48 by means of a hand lever 49 for the proper alining and engaging of the socket 34 thereof with the nutted end of a rail fastening bolt, the hand

lever 49 being released for the action of the 65 spring 48 to move the socket end of the wrench into such engagement. The lower end of the hand lever 49 is formed to provide a yoke 50, which has its free ends engaged in the opposite sides of a ring or collar 51 loosely seated in an annular groove 52 formed between a pair of annular flanges formed around an intermediate portion of the wrench head or member 33, and this lever is pivoted as at 53 to an upper cross 70 bar 54 extending transversely of the auxiliary frame and connecting the upper horizontal bars 14 thereof.

From the foregoing, it will be readily apparent that, while a preferred embodiment 80 of the machine has been described and illustrated herein in specific terms, and details of construction, arrangement and operation, various changes in and modifications of the same may be resorted to without departing 85 from the spirit of the invention or the scope of the claims appended hereto.

Having thus fully described the invention, what is claimed, is:—

1. In a machine wrench a vertically disposed frame having its lower portion adapted to extend over the tread of a rail and to oppose the web and base of the rail, an auxiliary frame projecting outwardly from that portion of the vertical frame opposing the web and base of the rail, a nut removing element carried by the auxiliary frame, operating means for said element mounted on the said frames, clamping elements pivotally connected to the lower portion of the vertical frame, and having foot portions adapted to engage the rail on that side of the latter opposite the side to which the vertical frame is positioned, and levers pivotally connected to the upper ends of the clamping elements and to said vertical frame at a point above the pivots of said clamping elements.

2. In a machine wrench a vertically disposed frame, an auxiliary frame projecting laterally of the lower portion of the vertical frame, a shaft supported wholly by the auxiliary frame, a driving mechanism for said shaft carried by said auxiliary frame, a wrench head slidably mounted on said shaft 110 and rotatable therewith, a manually operated lever pivoted to the auxiliary frame for shifting said head to operative position, a resilient member connected to said lever and to the vertical frame for maintaining said head in inoperative position, and operating means carried by said vertical frame and operatively connected with said driving mechanism.

In testimony whereof, we affix our signatures hereto.

RUDOLPH KLEIN.
GEORGE B. RITZEL.
